UNITED STATES PATENT OFFICE.

ALFRED CARLSON, OF KLAMATH FALLS, OREGON.

GEARING.

1,297,092.

Specification of Letters Patent. Patented Mar. 11, 1919.

Application filed March 28, 1918. Serial No. 225,257.

To all whom it may concern:

Be it known that I, ALFRED CARLSON, a citizen of the United States, residing at Klamath Falls, in the county of Klamath and State of Oregon, have invented certain new and useful Improvements in Gearing, of which the following is a specification.

The present invention relates to improvements in gearing by means of which driving power is transmitted to driven parts to do work. The general object may be said to consist in the provision of a simple assemblage of parts in such relation as to permit of maintenance of lubrication, requiring the minimum amount of replenishment and eliminating likelihood of leakage.

Another object is to provide means of this class for converting rotary motion of the driving element into rotary motion of the driven element.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a vertical sectional view through an embodiment of this invention;

Fig. 2 is a horizontal sectional view on the line 2—2 of Fig. 1; and

Fig. 3 is a fragmentary sectional view taken about on the plane indicated by the line 3—3 of Fig. 2.

Throughout the following detail description and on the several figures of the drawings, similar parts are referred to by like reference characters.

The embodiment of the invention herein described is depicted in its adaptation to windmill constructions but I do not desire to be restricted to such type of embodiment inasmuch as the mechanism is capable of being utilized for other purposes.

Referring to the drawing and specifically describing the device, 1 indicates a casing which in this instance constitutes an oil reservoir, a cover 2 being provided for said casing and suitably fastened thereto by conventional means as indicated at 3. Extending into the casing from one side is arranged the drive shaft 4 which in this application of the device is the shaft for the wind wheel (not illustrated). The shaft at its inner end

is journaled in the adjustable box or bearing 5 and at an intermediate point at the opposite side of the casing 1 in a similar box 6. Said shaft carries within the casing a bevel drive pinion 7 keyed to said shaft and arranged to actuate the planetary gear unit 60 now to be specifically described.

The unit just referred to consists of a frame formed by the lower plate 8 which, as will be observed particularly in Figs. 2 and 3, is formed with suitable spaced lugs 9 on its upper surface to which the upper plate 10 of the frame is secured by the fastening means or screws 11. The plates are arranged in spaced relation and held thus by the lugs 9 above referred to, and journaled between 70 said plates are the outer pinions 12, 12 meshing with an annular gear rack 13 formed on interior and lower portion of the casing 1. A driven shaft 14 which in this mechanism would be the vertical pump rod, 75 extends upwardly through the bottom of the casing 1 to a point substantially centrally thereof where it is fixed to the offset hub 15 of the central gear 16 of the planetary unit, by means of the pin 17. The 80 outer pinions 12 above referred to mesh with this gear 16 at opposite sides thereof. At this point it may be especially noted that one of the distinct features of this gearing arrangement is the offsetting of the hub 15 so 85 that it extends to a point above the level of the lubricant which is contained in the casing 1. It will be obvious that since the oil level is below the upper extremity of the shaft, said oil will not have a tendency to 90 leak from the casing, the leakage being precluded by utilizing a sleeve 18 surrounding the shaft 14 and having threaded connection at 19 with the casing. This sleeve 95 extends upwardly to a point adjacent to the upper portion of the hub 15 and the bore of the sleeve is preferably larger than the diameter of the shaft 14 so that no frictional contact will be made with said sleeve.

Surrounding the sleeve and intermediate 100 same and the gear 16 I preferably introduce a brass bushing 20 and the lubricant is distributed to the friction surface of this bushing by drippings which flow from the inclined drive shaft 4 and pass through the oil 105 passages 21 extending through the hub 15. Motion is obtained from the drive shaft 4 and its bevel gear 7 through the horizontal

bevel gear 22 which is fixedly secured to the upper surface of the upper plate 10 by the fastening means or screws 25.

From the foregoing it will be obvious that 5 rotation of the shaft 4 will actuate the bevel gear 7, in turn transmitting its motion to the gear 22 which transmits its rotary motion to the planetary gear frame and by reason of the intermeshing relations of the 10 outer pinions 12 with the casing rack 13 the frame revolves about the shaft 14 as an axis and the latter is rotated by the gear 16 incident to such rotation of the frame. Therefore, the rotary motion of the drive shaft 4 15 is taken off to do work by revolution of the driven shaft 14 for actuating the pump mechanism of the windmill, not herein illustrated.

The boxes or journals of the drive shaft 4 20 are lubricated by the lubricant contained in the casing 1 which is carried up by the gear 7 from its contact with the gear 22 and passes downwardly on the shaft in the manner hereinbefore indicated. To insure that the box 25 6 is properly lubricated I provide the gear 7 with a projecting arm 24 which carries the lubricant about the shaft and allows it to drip upon the upper surface of the box 6 from whence it passes through the passage 30 25 to the bearing.

The construction above described, it will be apparent, constitutes a windmill head and the casing is suitably formed with offstanding apertured spaced supports 26 on which 35 the vane or rudder of the windmill is attached. The base or under surface 27 of the casing acts as a turn table contacting surface enabling the free rotation of the windmill head upon the turn table in the usual manner.

40 Having thus described my invention, what I claim as new is:

1. In power transmission mechanism of the class described, the combination of a 45 casing for containing lubricant, a drive shaft extending thereinto and inclining downwardly, a drive pinion on said shaft, a driven shaft, gearing operatively connected to the shafts, and a projection on the drive pinion for picking up lubricant from the 50 casing to convey the same to the drive shaft bearings.

2. In power transmission mechanism of the class described, the combination of a 55 casing for holding lubricant, and including a gear element, a drive shaft projecting thereinto, a drive pinion mounted thereon, a driven shaft extending into said casing, planetary gearing mounted in the casing and operable by the drive pinion aforesaid, said 60 gearing including a gear member having an

offset hub extending above the level of the lubricant and with which the driven shaft is fixed for rotation.

3. In power transmission mechanism of the class described, the combination of a 65 casing for holding lubricant, a drive shaft projecting thereinto, a drive pinion mounted thereon, a driven shaft extending into said casing, planetary gearing mounted in the casing including a frame consisting of a bottom plate having spacing lugs thereon, an upper plate attached to said lugs, gear elements mounted between said plates, and a relatively large gear secured to the upper plate and driven by the drive shaft, said 70 driven shaft being secured to said gear elements for operation thereby.

4. In power transmission mechanism of the class described, the combination of a 75 casing, a drive shaft extending thereinto, a drive gear mounted thereon, a vertical driven shaft extending into said casing, and planetary gear elements operatively connecting the drive shaft with the driven shaft and comprising a frame consisting of spaced 80 side members, outer pinions journaled between said frames, a central gear member with which said outer pinions mesh, said central gear element having an offset hub projecting above the lubricant level, and a 85 relatively large gear attached to said frame and meshing with the drive gear on the drive shaft, and an annular rack on the casing with which the outer pinions of the planetary gear elements mesh.

5. In power transmission mechanism of the class described, the combination of a 90 casing, a drive shaft extending thereinto, a drive gear mounted thereon, a vertical driven shaft extending into said casing, 100 planetary gear elements operatively connecting the drive shaft with the driven shaft and comprising a frame consisting of spaced side members, outer pinions journaled between said frames, a central gear member 105 with which said outer pinions mesh, said central gear element having an offset hub projecting above the lubricant level, a relatively large gear attached to said frame and meshing with the drive gear on the drive 110 shaft, an annular rack on the casing with which the outer pinions of the planetary gear elements mesh, and a sleeve surrounding the driven shaft and extending into the hub of the central gear element of the planetary 115 gearing, said sleeve having connection with the casing and constituting means for preventing escape of lubricant from the casing.

In testimony whereof I affix my signature.
ALFRED CARLSON.
